LAUNDRY CHECKING DEVICE

Filed March 21, 1930

INVENTOR:
JOHN H. TODD

By George W. Saywell
ATTORNEY

UNITED STATES PATENT OFFICE

JOHN H. TODD, OF CLEVELAND, OHIO, ASSIGNOR TO THE KEY-TAG CHECKING SYSTEM COMPANY, OF CLEVELAND, OHIO, A CORPORATION OF OHIO

LAUNDRY CHECKING DEVICE

Application filed March 21, 1930. Serial No. 437,698.

My invention particularly relates to improvements in checking devices of the character shown and described in United States Letters Patent Nos. 1,343,423, and 1,399,906, issued upon my inventions in laundry-checking devices. As is well known to those skilled in the art, the primary object of such devices is to insure the proper segregation into different classes, or on behalf of different owners, of laundry articles or nets of such articles which have been indiscriminately commingled during the operations incident to the laundering thereof. These present improvements contemplate a greater flexibility in the use of, a more reliable and convenient operation of, and an increase in the capacity of, such checking devices. The construction whereby these advantages are attained will be hereinafter described in detail.

The annexed drawings, and the following description set forth in detail certain means embodying the invention, the disclosed means, however, constituting but one of the various mechanical forms in which the principle of my invention may be applied.

In said annexed drawings:

Figure 1 is an elevation of my improved checking device detachably supported at one end upon a main frame and having depending from one of its arms three pieces of laundry as illustrative of the use of the device;

Figure 2 is a plan view of the device, partially in section, taken from the plane indicated by the line 2—2, Figure 1;

Figure 3 is a longitudinal section, taken in the plane indicated by the line 3—3, Figure 2;

Figure 4 is a longitudinal section, taken in the plane indicated by the line 4—4, Figure 2;

Figure 5 is a transverse section, taken in the plane indicated by the line 5—5, Figure 2;

Figure 6 is a transverse section, taken in the plane indicated by the line 6—6, Figure 2;

Figures 7, 8, 9, and 10 are elevations of four forms of check-members forming part

of my improved laundry-checking device; and

Figure 11 is a plan view of a plate member secured to one of the arms of a hanger forming part of the device, said plate member being adapted to cooperate with certain check-members in a manner and for a purpose hereinafter fully described.

Referring to the annexed drawings, in which the different parts are indicated by the same respective numbers in the several views, there is secured to a main support 1, such as a building wall, or any suitable movable or fixed frame or abutment, a bracket 2 having a main or base portion 2' and an over-hanging reentrant lip 3, this base portion 2' and lip 3 forming means for holding at one end an outwardly-extended arm 5 of a laundry hanger whose longitudinal movement relatively to the bracket portion 2' is prevented by means of a downwardly-projected lug 6 formed upon and punched from the material of the arm 5 and adapted to engage a hole 4 formed in the bracket base 2', as plainly shown in Figure 4. The construction is such that, upon lifting the outer end of the arm 5, the lug 6 can be disengaged from the hole 4, and then the arm 5 pulled out of the bracket 2.

Secured to the arm 5 and extended substantially in parallel relation therewith, but laterally spaced therefrom, is a second arm 7—8 which, in the construction shown for purposes of illustration, consists of the relatively right angular portions 7 and 8, the portion 7 being secured to the arm 5 and at right angles to the latter, as plainly shown in Figure 2. These arms 5 and 8 form a hanger member and are intended to support segregated laundry pieces or laundry nets, it being contemplated that laundry pieces or nets of one character only shall be supported upon the arm 5, and of one character only upon the arm 8, the pieces or nets upon the two arms 5 and 8 differing from each other in character, although preferably belonging to the same individual or class. For purposes of illustration, it is contemplated that comparatively large laundry pieces of, or large nets for, an individual are segregated

gated upon the arm 5, and smaller pieces or nets for the same individual upon the arm 8. This segregation is effected by means of the character shown and described in said 5 two U. S. Letters Patent Nos. 1,343,423, and 1,399,906.

These segregating means comprise check-means 9, 12, 14, and 14', shown in Figures 9, 8, 7, and 10, respectively, adapted for co-10 operation with certain projections formed upon the arms 5 and 8. The check members 12, 14, and 14' are of similar character, insofar as the checking operation is concerned, but the three said check-members are shown 15 in order to illustrate different methods of attaching the same to the laundry pieces or nets. The cooperating means upon the check-members 9, 12, 14 and 14', and arms 5 and 8 comprise registering slots and pro-20 jections; for instance, the slot 19 in the check-member 9 adapted to receive the body of the arm 5, this slot 19 having substantially the same longitudinal dimension as the width A—B, Figure 2, of the arm 5, this 25 check-member 9 further being formed with slot portions 20 and 21 which receive the respective upper and lower projections 22 and 23 formed upon the arm 5 and adjacent the outer end of the latter. Thus, the 30 check-member 9 can be fitted to the arm 5, which latter is in effect a key for said check-member, and for all check members having the same cooperating slot outlines. These 35 similar check-members, of course, are fastened to the different laundry pieces or nets of the same individual or class, and remain so attached during the laundry operations, and by their cooperation with the arm or key 5, when it is desired to segregate the 40 laundry, insure a segregation by individuals or classes. A suitable number of the hangers and their respective cooperating check-members comprise a series or set of checking devices which serve for the commingled 45 laundry of all the persons or the classes of laundry which later should be segregated for several distributions to the different owners. This feature of the invention and this principle is fully described in said above-mentioned Letters Patent.

I have further provided the arm 5 with means which prevent the accidental slipping of the check-members 9 and their depending loads from the arm 5, and yet permit the ready threading of the check-members and their loads inwardly of the arm as far as desired. These means comprise a plate spring 25 secured at one end within a recess 24 formed in the arm 5, said plate 55 spring 25 being formed adjacent its opposite end with an angular portion 25' which normally extends upwardly beyond the upper face of the arm 5 but can be depressed below said face so as to permit the passage 60 of the check member 9 thereby, this angular

portion 25' of the spring 25 sloping in both directions from a substantially central ridge point so as to present an inclined surface to the check-member 9 in both directions of travel of the latter and thus permit easy 70 passage of the check-member. Thus the spring portion 25' is depressed by the pressure of the check-member in the hand of the operator, as the latter threads the laundry upon the arm 5 or removes it therefrom. 75

Likewise, the arm 8 cooperates with check-members 12, 14, and 14', the outline of the slots in these three check-members being the same. The purpose in showing three of these 80 check-members will be given later. Describing one of these outlines, it will be noted that there is a slot portion 35 of substantially the same vertical extent as the depth C—D of the arm 8, Figure 1, the check-member being further formed with slot portions 36, 85 39, and 41 which cooperate respectively with projections 37—38, 40 and 42 formed upon the arm 8 and adjacent the outer end of the latter. These projections are in reality 90 formed in a horizontal plate 31, Figures 2, 90 and 11, the width E—F, Figure 2, of which corresponds substantially to the longitudinal extent of a slot portion 34 formed in the check-member, this plate 31 being secured intermediate the top and bottom of the arm 8 and in a horizontal fissure or slit 33 formed in the latter and adjacent the outer end thereof, and extending laterally upon both 95 sides of the arm 8, as shown in Figure 2. In order that the transverse plate member 31, 100 may be securely held in the fissure 33 formed in the arm 8, a vertical rivet 32 which intersects the outer end of the plate 31 is passed through and secured in said arm 8; and, furthermore, to insure the plate 31 positively 105 against lateral movement, it is formed with a notch 31' which is tightly engaged by the arm 8, the fissure 33 in said arm not extending inwardly as far as the plate 31, as plainly 110 shown in Figure 2. Various positions of the 115 plate 31 in the arm 8, as regards the respective amounts of lateral extension thereof upon the two sides of the arm 8, as also the height of the holding fissure 33 in said arm, afford increases in the number of different check-member outlines which may be used with the same size plate 31 and same arm 8. Of course, any variation in the size or position of the projections 38, 40 and 42 will also increase the possible combinations without any 120 change in the size of the plate 31 or arm 8 or the position of the plate in the arm.

The arm 8 is also provided with a plate spring having a portion 47 normally extended above the surface of the top face of the 125 arm 8 and adapted upon pressure of the check-member thereon to permit the latter and its laundry load to be mounted upon the body of the arm 8. However, this spring 47 does not permit the check-member to be re- 130

moved from the body of the arm 8 unless the spring is depressed manually, as plainly shown in Figure 1. The depressible end of the spring 47 is formed into a downwardly-extended flanged end portion 47' which is disposed in a recess 45 formed in the arm 8 and of suitable configuration, whereby an overhanging lip portion 8' of the arm 8 forms a stop to the outward movement of the spring 47 by engaging the flange 47', as shown in Figure 1. The spring 47 is secured by rivets 46, one of which in the form of device shown in the accompanying drawings intersects the plate 31. The rounded and upturned outer ends 48 and 49 of the arms 5 and 8, respectively, permit the convenient threading of the check-members thereon.

The laundry pieces or laundry nets can be fastened to the check-members 9, 12, 14 and 14', in various ways. In Figure 9, I have shown the check-member 9 formed with a hole 16 through which a ring 27 is passed, the ring 27 also passing through the coils at one end of a pin 54, which pin is fastened to the laundry net. In Figure 8 I have shown the check-member 12 directly engaging a safety pin 17 which can be secured to the laundry piece 28, the pin in this form of check-member being pivotally secured to the check-member body. In Figure 7, I have shown the check-member 14 provided with a ring 18 which is passed through a pin 30 secured to the laundry piece 29, Figure 1. In Figure 10, the check-member 14' is rigidly secured to the pin 55, the hasp-arm 55' of the latter being formed into a loop 55' which is contained within a peripheral pocket 14' formed in the check-member body 14'. The pin member 55 is secured to the laundry piece 56, Figure 1, and the arm 55' is provided with a hasp 57 adapted to be detachably engaged in the manner common to safety pin operation.

It will be noted that the check-members and the cooperating hanger are keyed by corresponding insignia 10—11—13—15—15', the insignia in the accompanying drawings for purposes of illustration being numbers "30".

50 The described and illustrated improvements provide a conveniently operated and durable checking device and hanger of large capacity. The double-arm hangers accommodate a substantially larger number of laundry pieces or nets than single-arm hangers accommodating pieces or nets in the same space. The hangers are portable with the laundry depending therefrom and the latter cannot accidentally slip from either end of the arm 5 or the arm 8. When not in use, the hangers can be removed from the brackets 2 and vertically suspended by means of any convenient hole 51, 52, or 53 formed in the several end portions thereof, a plurality of the hangers with corresponding

check-members usually being transported and stored on a suitably-shaped hooked carrier.

What I claim is:

1. A hanger for laundry-checking devices, comprising a main arm adaptable for detachable connection to a support and an auxiliary arm secured to said main arm and extended in laterally spaced and generally parallel relation to the latter, each of said arms having means, adjacent an end of such arm, for permitting passage of check-members of predetermined formation onto the body of such arm and excluding check-members of other formations therefrom. 70

15 75 80

2. A hanger for laundry-checking devices, comprising a bracket adapted for rigid attachment to a supporting frame, a main arm adapted for removable support at one end in said bracket, and an auxiliary arm secured to said main arm and extended in laterally spaced and generally parallel relation to the latter, each of said arms being provided with means for permitting passage of check-members of predetermined formation and excluding check-members of other formations. 85

20 90 95 100

3. A hanger for laundry-checking devices, comprising a main arm adaptable for detachable connection to a support and an auxiliary arm secured to said main arm and extended in laterally spaced and generally parallel relation to the latter, each of said arms being provided with means for permitting passage of check-members of predetermined formation onto the body of such arm and excluding check-members of other formations therefrom, and compressible plate springs normally intersecting face surfaces, respectively, of said arms. 105

25 110 115 120

4. A hanger for laundry-checking devices, comprising a bracket adapted for rigid attachment to a supporting frame, a main arm adapted for removable support at one end in said bracket, and an auxiliary arm secured to said main arm and extended in laterally spaced and generally parallel relation to the latter, each of said arms being provided with means for permitting passage of check-members of predetermined formation and excluding check-members of other formations, said bracket having an overhanging reentrant lip under which an end of said main arm extends, and said bracket and said main arm having a cooperating slot and projection, respectively, to insure the engagement of said bracket and arm against relative lengthwise movement. 125

5. In a checking device, the combination with an apertured check-member adapted for connection to the article to be checked; of a key having a transverse cross-section of an outline adapting the check-member to be fitted to the key, the latter being provided with a plate spring having a portion normally intersecting a face surface of the key, 130

and said spring being resistant to the passage of the check-member over said surface and having a second portion movable toward said surface by pressure exerted through the 5 check-member to permit the latter to pass the spring.

6. In a checking device, the combination with a plurality of apertured check-members adapted for connection to the articles to 10 be checked; of a hanger comprising a main arm adaptable for detachable connection to a support and an auxiliary arm secured to said main arm and extended in laterally spaced relation to the latter, said arms being 15 formed with transverse cross-sections of outlines, respectively, adapting some of said check-members to be fitted to each arm, each of said check-members fitting at least one of said arms, each of said arms being provided 20 with a plate spring having a portion normally intersecting a face surface of the arm and resistant to the passage of check-members over said surface.

7. In a checking device, the combination 25 with a plurality of apertured check-members adapted for connection to the articles to be checked; of a hanger comprising a main arm and an auxiliary arm secured to said main arm and extended in laterally spaced relation to the latter, said arms being formed 30 with transverse cross-sections of outlines, respectively, adapting some of said check-members to be fitted to each arm, each of said check-members fitting at least one of said 35 arms, each of said arms being provided with a depressible plate spring normally intersecting a face surface of the arm and resistant to the passage of the check-member over said surface, one of said springs being movable 40 toward the adjacent arm surface by pressure exerted through the check-member to permit the latter to pass the spring, and the other spring being manually depressible to permit the passage of the check-members 45 outwardly of the arm.

8. In a checking device, the combination with a plurality of apertured check-members adapted for connection to the articles to be checked; of a hanger comprising a main arm 50 and an auxiliary arm secured to said main arm and extended in laterally spaced relation to the latter, said arms being formed with transverse cross-sections of outlines, respectively, adapting some of said check-members to be fitted to each arm, each of said 55 check-members fitting at least one of said arms, each of said arms being provided with a plate spring having a portion normally intersecting a face surface of the arm and 60 resistant to the passage of check-members over said surface, one of said springs being movable toward the adjacent arm surface by pressure exerted through the check-member to permit the latter to pass the spring, the 65 other spring being formed with a down-

wardly-extended flanged end, and the adjacent arm being formed with a recess containing said flanged end and permitting a vertical reciprocating movement therein of said flanged end, said arm being formed with a stop limiting the upward movement of said spring end, the last-named spring being manually depressible to permit the passage of check-members thereby outwardly of the arm.

9. In a hanger for laundry-checking devices, an arm having a body portion and a check-registering portion, the latter portion being near an end of said arm and having a plate secured thereto so as to have an edge 80 facing toward said end, said plate extending beyond a surface of said arm and having a projection extending from its surface, and said plate and projection having a predetermined formation for permitting passage of 85 check-members having a formation corresponding to said predetermined formation onto said body portion and excluding check-members of other formations.

10. In a checking device, an arm having a 90 body portion and a check-registering portion, the latter portion being near an end of said arm and being formed with a slit, and a plate mounted in said slit and fixed to said arm, said plate extending beyond oppositely 95 disposed surfaces of said arm and having projections extending from its surface, and said plate and projections having a predetermined formation for permitting passage, onto said body portion, of check-members 100 having a formation corresponding to said predetermined formation and for excluding from said body portion check-members of other formations.

11. In a checking device, an arm having a 105 body portion and a check-registering portion, the latter portion having a plate fixed thereto, said plate extending beyond a surface of said arm and having a projection 110 extending from its surface, and the formation of said plate and projection and the position of said plate and projection relative to said arm being such as to permit passage, onto said body portion, of check-members of predetermined formation and to exclude 115 from said body portion check-members of other formations.

Signed by me this 4th day of March, 1930.

JOHN H. TODD. 120
